UNITED STATES PATENT OFFICE.

BERNARD CONLAN, OF NEWARK, NEW JERSEY.

DESIGN FOR A CLASP.

SPECIFICATION forming part of Design No. 32,358, dated March 20, 1900.

Application filed January 3, 1900. Serial No. 293. Term of patent 31 years.

To all whom it may concern:

- Be it known that I, BERNARD CONLAN, a citizen of the United States, residing at Newark, in the county of Essex and State of New Jersey, have invented and produced a new and original Design for Clasps, of which the following is a specification, reference being had to the accompanying drawings, forming a part thereof.
- 10 The design presented is a clasp in the form of a miniature padlock. In describing it I will call attention to the accompanying drawings, where like letters of reference indicate corresponding parts in both views.
- 15 Figure 1 shows a front view of the clasp, and Fig. 2 a side view thereof.
- It consists of two parts A and B, A indicating the main body of the clasp, formed as a padlock in the shape of a heart, and B a
- 20 hinged member forming a part of an arm protruding from the main body.

C, D, E, F, and G are indents produced to indicate the keyhole and rivet-heads in an ordinary padlock.

This article is constructed in miniature size 25 to be used as a clasp for ladies' belts or similar purposes, the attached figures being somewhat enlarged for the sake of clearness in illustration.

Having thus described my design, what I claim is—

The design for a clasp as herein shown and described.

In testimony that I claim the foregoing I have hereunto set my hand this 2d day of 35 January, A. D. 1900.

BERNARD CONLAN.

Witnesses:

JOHN O'NEIL,
AUGUST M. TRESCHOW.
